UNITED STATES PATENT OFFICE

2,352,415

ARBOR HOLDER

Thomas M. Stephens, Montgomery, W. Va.

Application November 2, 1942, Serial No. 464,309

4 Claims. (Cl. 76—89.2)

This invention relates to devices for dressing rock drills and has as its principal object the provision of an arbor holder which will be simple in construction, economical in manufacture and highly efficient in use.

Another object of my invention is to provide in bit forming and shaping devices, a guide structure for holding a mandrel in axial alignment with forming dies.

A further object of this invention is to provide an arbor holder which will align drill bits to be worked upon with the machine acting upon the drill bit and simultaneously to lessen the shock produced by drop forge means acting upon the drill bit.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view of a used rock drill bit about to be mounted upon an arbor;

Fig. 2 is a perspective view of my new arbor holder illustrating the arbor with bit attached about to be placed in the holder;

Fig. 3 is a longitudinal vertical section through the same and taken along line 3—3 in Fig. 2

30

with the arbor in place;

Fig. 4 is an end elevational view of the arbor holder as seen from line 4—4 in Fig. 2; and

Fig. 5 is a perspective view of a finished rock drill bit after the dressing operation.

This invention has to do with machines for shaping and sharpening drop forged cutter bits such as the one illustrated in the drawing herein. Numerous types and kinds of cutter bits have been devised each differing in form as to the cutting face to provide cutter bits for various purposes. In the present disclosure there is shown, for the purpose of illustration, a four-pronged cutter bit 10 having a plurality of prongs 11 formed at its front face 12, such bit having a shank end 13 drilled out and provided with a standard inside thread 14 adapted for universal application to various forms of bit holders.

The bits herein disclosed are used in pneumatic rock breakers employed in demolishing concrete, stone and other such substances of like character. By reason of the rigorous abuse which these bits receive, it becomes necessary that they be redressed by a sharpening and

shaping process. Such is the nature of the machine with which the present invention is concerned. A used and distorted bit is shown in Fig. 1 about to be screwed onto the stud end 15 of a mandrel or arbor 16 whereby the bit may be handled during the redressing operation. The bit 10 is first placed in a forge and brought to a suitable forging heat. By means of tongs (not shown) the bit 10 is held while the stud 15 is screwed into the thread 14 on the shank 13. The arbor 16 now forms a tool holder for the bit which is placed under a vertical drop forge (not shown) to straighten the prongs 11 and dispose them substantially parallel to the long axis of the bit 10. The arbor 16 with bit 10 attached is now ready to be placed in the arbor holder for the redressing process.

The arbor holder is generally indicated at 17 and has a pedestal 18 which is adapted to be affixed to a foundation by means of lag screws 19 or the like. A flange 20 is mounted at the upper end of the pedestal 18 and has bolted thereto as at 21 a bed plate 22. The bed plate is aligned with a horizontal drop forging machine, generally indicated at 30 and later to be mentioned, and is provided with a guide block 23 at one end which block 23 is suitably bolted to the bed plate 22. The block 23 has a yoke formation 24 into which may be placed the arbor 16 for holding the latter in the plane of the hammering machine. There is a screw block 25 bolted adjacent the opposite end of the bed plate 22 which screw block 25 has an elongated threaded opening 26 aligned with the yoke formation 24. A threaded arbor 27 having a hand wheel 28 at one end is screwed into the opening 26 and presents an abutment face 29 which is adapted to be adjusted and set against the butt end 31 of the arbor 16 to take up the shock produced by the horizontal drop forging machine 30.

The forging machine 30 may be any one of a number of well known types which include a horizontally reciprocable hammer (not shown) for reciprocation over a bed plate 32 and carrying a forming head 33. In conjunction with my arbor holder there is provided a forming die or anvil 34. This anvil 34 is preferably mounted on the end of the bed plate 32 of the horizontal forging machine 30. This anvil 34 is placed as aforesaid in alignment with the reciprocable hammer head 33 and an axial plane struck through the yoke 24 and the threaded arbor 27.

The anvil 34 is formed to provide an abut-

ment shoulder 35 which is adapted to abut a collar 36 formed on the arbor 16 adjacent the stud 15 and against which collar 36 the shank 13 is screwed (Fig. 3). The anvil 34 is also provided with a semi-annular groove 37 into which the collar 36 is placed while the shank of the arbor 16 is rested in a trough 38 formed in the abutment shoulder 35.

It will be remembered that the bit 10 when screwed onto the arbor 16 is heated to a forging temperature so that the fibre thereof may readily be shaped by the force of a drop forge hammer. The bit 10 having already been conditioned as aforesaid with the prongs 11 substantially parallel to the long axis of the bit, the bit and arbor 16 are now placed in the anvil 34 and yoke 24 respectively, the threaded arbor being screwed up with the abutment face 29 in abutting relation with respect to the butt end 31 of the arbor 16 as shown in Fig. 3.

The anvil has a die formation 39 at its edge closest adjacent the hammer head 33 and it will be understood that this die formation 39 may be varied in form to correspond in shape to the particular type of bit being dressed.

With the arbor 16 and bit 10 thus placed in the arbor holder 17, the horizontal drop forge machine 30 is operated to cause the hammer and head 33 to reciprocate several times with the head 33 inflicting several blows against the face 12 of the bit, thus causing the prongs 11 to resume a shape defined by a crevice 11' formed in the die formation 39 of the anvil. The arbor 16 is lifted by hand from the yoke and anvil to rotate other prongs 11 into position with respect to the crevices 11', and the hammer head 33 again reciprocated against the face 12 of the bit until finally the cutting bit is redressed to present again a uniformly shaped and sharpened cutting face. The bit is then unscrewed and allowed to cool and thereafter is ready for use as a rock drill, the final product being illustrated in Fig. 5.

It will be noted that by reason of the arrangement of the anvil 34 and its grooves 37 and trough 38, together with the yoke 24 in block 23 and the abutment provided by the threaded arbor 27, the mandrel or arbor 16 may be casually placed in position by hand and will assuredly be snugly held in alignment with the line of force from the drop forging machine 30. Also, the abutment shoulder 35 will hold the red hot bit 10 in position to receive the blows from the hammer head 33 and will take the shock of such blows as will the threaded arbor 27, thus assuring a firm foundation for the whole instrument being worked upon and relieving shearing action at the point where the collar 36 joins the shank of the arbor 16.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A device for holding a drill head on an anvil in alignment with a trip hammer of a drop forge comprising an arbor for holding said drill

head, a collar on said arbor, a groove formed in said anvil and forming a seat for said collar, an adjacent wall of said groove providing a vertical abutment for said collar and adapted to maintain said arbor and drill head in position when blows are inflicted as aforesaid, and means co-operating with said groove and abutment to support said arbor in axial alignment with the line of force of said hammer, said last named

means comprising a pedestal, a bed plate supported by said pedestal, a yoke block on said bed plate and disposed in axial alignment with said hammer and said anvil to receive said arbor and align the latter with the hammer and anvil.

15 2. A device for holding a drill head on an anvil in alignment with a trip hammer of a drop forge comprising an arbor for holding said drill

head, a collar on said arbor, a groove formed in said anvil and forming a seat for said collar, an adjacent wall of said groove providing a vertical abutment for said collar and adapted to maintain said arbor and drill head in position when blows are inflicted as aforesaid, and means co-operating with said groove and abutment to sup-

25 port said arbor in axial alignment with the line of force of said hammer, said last named means comprising a yoke block disposed in axial alignment with said hammer and said anvil to receive said arbor and align the latter with the hammer and anvil,

30 and an abutment for said arbor and arranged on the side of said yoke opposite to said anvil and adapted to absorb shock conveyed along said arbor from the hammer.

35 3. A device for holding a drill head on an anvil in alignment with a trip hammer of a drop forge comprising an arbor for holding said drill

head, a collar on said arbor, a groove formed in said anvil and forming a seat for said collar, an adjacent wall of said groove providing a vertical abutment for said collar and adapted to maintain said arbor and drill head in position when blows are inflicted as aforesaid, and means co-operating with said groove and abutment to sup-

40 port said arbor in axial alignment with the line of force of said hammer, said last named means comprising a pedestal, a bed plate supported by said pedestal, a yoke block on said bed plate and disposed in axial alignment with said hammer and said anvil to receive said arbor and align the latter with the hammer and anvil,

45 and an abutment for said arbor and arranged on the side of said yoke opposite to said anvil and adapted to absorb shock conveyed along said arbor from the hammer.

50 55 4. A device for a rock drill dressing machine, which machine includes a reciprocable hammer head for inflicting blows against a rock drill bit and an arbor for holding said rock drill bit, comprising an anvil disposed to receive blows from said hammer head and providing a yoke

60 formation and a shoulder adjacent thereto, a collar formation on the arbor adapted to lie against said shoulder to hold the rock drill bit between said anvil and the hammer head, and a

65 guide block spaced from said anvil on the side thereof opposite the hammer head and adapted to receive the arbor to hold the latter in alignment with said anvil and hammer head, and an abutment for the arbor and arranged on the side of said guide block opposite said anvil in alignment with the latter and the hammer head

70 to absorb the shock conveyed through the rock drill bit and said arbor from the hammer head.

THOMAS M. STEPHENS,
